(57) **CLAIM**

The ornamental design for an articulating head component for ceiling fan blade cleaner, as shown and described.

DESCRIPTION

FIG. 1 shows the front elevation view of an ornamental design of an articulating head component for ceiling fan blade cleaner;

FIG. 2 shows a back elevation view thereof;

FIG. 3 shows a top plan view thereof;

FIG. 4 shows a bottom plan view thereof;

FIG. 5 shows a right elevation view thereof; and,

FIG. 6 shows a left elevation view thereof.

The broken lines depict portions of the articulating head component for a ceiling fan blade cleaner that form no part of the claimed design.

1 Claim, 2 Drawing Sheets
